AUTOMATIC CLOSURE

Thomas S. McIntire, Wakefield Mass.

Application April 5, 1933, Serial No. 664,543

9 Claims. (Cl. 268—11)

This invention relates to improvements in automatic closures. More especially it relates to closures for floor holes and the like, where it may be desired to have a hole normally closed against 5 drafts, fumes, etc. and to have its closure open quickly and automatically when an object or a person is to pass through the hole.

For purposes of the present disclosure, the invention will be described in its application to 10 sliding-pole holes, such as are used in fire and police stations, and through which men descend from one floor to another by sliding down a pole.

Firemen in particular, while on duty at a fire station, are subject to momentary call, and are 15 required to be at their respective posts on the fire apparatus in the shortest possible time after an alarm is sounded. Between calls, the men ordinarily engage themselves about the premises; and usually quarters are provided for them on a floor 20 above the place of garaging of the apparatus.

The sliding-pole method of descent from an upper to a lower floor has been quite generally adopted as the best and quickest way of assembling the manning force for the apparatus. But 25 the relatively large floor hole necessary to permit safe passage of a man down a pole is a source of great annoyance when left normally uncovered. A strong and discomforting draft is occasioned from one floor to another; and objectionable 30 fumes from the apparatus pass up into the living quarters above.

Various proposals have been made heretofore 35 for closing these floor holes when the sliding-poles are not in use, and for opening them as a preliminary to their use. But the prior proposals have been both unsafe and unsatisfactory. Some 40 have involved the necessity of closing an electric circuit which in turn effected an upward swing of a trap door; and others have had a plate closure which, upon closing of an electric circuit, is made to run up the pole, thereby opening the 45 floor hole. In both of these cases valuable time is lost waiting for the way to be cleared. And there is always danger of serious injury to a man 50 who, in the hurry and excitement, and often in pitch darkness, may enter onto the sliding-pole before the closure has moved completely out of the way, and be caught by the trap door, or be knocked senseless by the upward travelling plate closure.

It is among the objects of the invention to eliminate all preliminaries to the free and safe passage of a man through a normally closed sliding-pole hole.

55 Another object is to ensure that the closure will spring wide open the moment that a man comes on the sliding-pole.

A further object is to provide so that the opening travel of the closure will be in directions away 60 from a man coming onto the pole.

Still another object is to provide a guard around the floor hole which conveniently may cooperate in accomplishing the automatic operation of the closure.

It is, moreover, an important feature that the 65 invention may be employed with a sliding-pole suspended from a ceiling, or mounted in the guard structure; or the pole may be mounted in a separate supporting structure.

The stated objects and results may be attained 70 by employing the sliding-pole as an actuator for operating the closure to its open and to its closed positions. To this end the pole is yieldably mounted so that it depresses a little in vertical direction when a sufficient downward pressure 75 is made effective upon it. Suitable operating connections between the closure and a high-up location on the pole translate any vertical travel of the pole into rotatory travel of the closure, to move the latter, about pivotal points, between 80 open and closed positions. Spring tension normally may hold the pole in its uppermost position at which times the closure will be effectively covering the floor hole. But the moment a man comes onto the sliding-pole, he applies to the 85 pole the weight needed to depress it and thus to actuate the closure to clear the floor hole for his safe, sliding passage through.

It is intended that the patent shall cover, by 90 suitable expression in the appended claims, whatever features of patentable novelty exist in the invention disclosed.

In the accompanying drawings:

Figure 1 is an elevation, in medial vertical section through a sliding-pole hole in an upper floor 95 of a building, and showing a device embodying features of the invention, likewise in medial vertical section, associated therewith;

Figure 2 is a plan of the device of Figure 1;

Figure 3 is a plan, in section on 3—3 of Figure 1;

Figure 4 is an elevation, in medial vertical section on 4—4 of Figure 3;

Figure 5 is an elevation of a modified structure embodying features of the invention;

Figure 6 is a plan of the device of Figure 5;

Figure 7 is a plan, in section on 7—7 of Figure 5;

Figure 8 is an elevation, with the lower portion in vertical section on 8—8 of Figure 7, and with upper portions cut away to the center of the tubular structure;

Figure 9 is an elevation, in medial vertical section, of the yieldable ceiling suspension device 115 for holding the sliding-pole of Figures 5 and 6; and

Figure 10 is an elevation, in medial section, showing another modification of the invention, in which cables and counter-weights cooperate 120

with the sliding-pole, to effect opening and closing of a sectional closure.

Referring to the drawings, and particularly to Figures 1 to 4 thereof, lower and upper floors of a building are indicated respectively at 10 and 12, and a floor hole 14 in the upper floor 12 constitutes a passage way through which men on the upper floor may descend. A sliding-pole 16 stands vertically erect at the center of hole 14, 10 extending from a location well above floor 12 down to the lower level 10 where its end may slidably engage in a socket 18.

Pole 16 is shown suspended in a tri-pod supporting structure indicated generally at 20; and 15 a guard rail 22, at a suitable elevation, may encircle the tri-pod and form therewith a cage which stands in guarding relation to the floor hole 14. Any suitable form of gate may be provided for getting access to pole 16, such as the 20 hinged guard rail sections 22^a, 22^b, normally held closed by sliding sleeve 22^c. Or an opening may be left in the guard rail 22, at the entrance.

According to the invention sliding-pole 16 is mounted so that it depresses vertically when subjected to any substantial downward pressure. To 25 this end its tri-pod support is telescoping in character, each leg thereof having a rigid, tubular portion 24 within which a tubular portion 26 of smaller diameter extends and is compressible against the yielding tension of a spring 28 which conveniently may be housed within the rigid outer tube 24. Each of the compressible tubes 26 extends vertically upward six or more feet above 30 floor 12 where all turn inward as at 26^a and have their respective ends secured in the pole suspending cap 30.

The closure for floor hole 14 may be of the improved sectional form illustrated, and it conveniently may be arranged on the under side of 40 floor 12, which brings it in the ceiling of the compartment below. It is conical in form, comprising three segments 32, each hingedly mounted on its own horizontal axis 34, and all adapted to come together around pole 16 to completely and 45 effectively cover the hole 14; and all are adapted to swing downwardly and outwardly to clear the way for a man coming down the pole.

As illustrated a floor ring 36 is secured on floor 50 12, around the edge of hole 14, it having the upstanding bosses 36^a in each of which one of the rigid tubes 24 of the tri-pod may be threaded, and within each of which a rest 36^b may be provided for the lower end of one of the springs 28.

Another ring 38 is employed on the under or 55 ceiling side of floor 12, it being secured to the ceiling, and having three pairs of ears 38^a, each of which pairs supports a hinge pin 34 on which a closure segment 32 is mounted and about which, as an axis, the segment moves. Each segment 32 60 may have a body of suitable sheet material secured on a segmental carrier 32^a, with ears 32^b through which the hinge pins 34 engage.

Actuation of the closure segments 32 is responsive to movements of the sliding-pole 16 and its telescoping tri-pod support. Each tubular portion 26 of the tri-pod extends well down toward the horizontal plane of the closure; and the lower end of each has link connection to one of the segments 32, as at 40 in Figures 1 and 4.

70 Springs 28 normally are effective for holding the pole 16 in its uppermost position. They yield, however, the moment a man comes onto the pole 16, permitting the pole and its tri-pod portions 26 to be depressed by the weight of the man. Depression of tri-pod portions 26 causes downward

and outward swinging of the respective closure segments 32, all moving simultaneously and in unison, and each directly urged by its connector link 40. The amount of depression of pole 16 80 needed to effect complete opening of the closure, may be made as large or as small as is desired, by selection of a suitable leverage effect. As a practical matter, an inch or an inch and a half of depression of pole 16, tempered by the shock-absorbing characteristics of the springs 28, is hardly noticeable by a man using the pole. It is important, however, that the depression be complete and instantaneous consequent upon substantial pressure or weight coming onto the pole, so that complete opening of the closure will have 90 transpired before the man coming down the pole reaches the closure. As soon as the man leaves the pole at the lower level 10, the springs 28 act to return tri-pod and pole to normal positions, and thereby to cause the closure segments 32 to 95 assume their positions effectively covering the hole 14.

In Figures 5-9 a modified structure is illustrated wherein the sliding-pole 16^a is suspended from the ceiling of the upper compartment, and 100 extends eccentrically of floor hole 14^a. In this form of the invention the upper end of pole 16^a is yieldingly supported on spring 28^a which in turn is supported at its lower end, by a housing 42 secured to the ceiling. The guarding cage may 105 comprise four rigid tubular uprights 44, 46 with horizontal guard rails 48 connecting the uprights. The rail 48 at the entrance side may embody the hinged sections 48^a, with slidable locking sleeve 48^b. If desired, each gate section may be provided at its hinge with a spring 48^c normally urging the gate section inward, so that each automatically swings inward and out of the way as soon as the sleeve 48^b is moved to release it.

Only two of the uprights, however, cooperate 115 in actuation of the closure sections 50, 50'. The two rear uprights 46 in this case accommodate the telescoping actuating rods 52, whose upper ends are connected together and to pole 16^a by the truss 54.

The closure comprises two sections 50 and two sections 50', and each section is secured along its outer edge to a rocker shaft whose ends are journaled in suitable supporting hangers 56 at the under or ceiling side of floor 12^a. One 125 rocker shaft 58 acts as the prime mover for the other three rocker shafts 60. To this end the prime mover is located along the rear side of hole 14^a, and carries at each end a lever 62 which reaches over toward the axis of one of 130 the actuating rods 52, and upward to a slotted connector 64 secured in the lower end of each rod 52. Lever 62 has pin and slot connection to connector 64, so that vertical movement of the actuating rods causes rocking of shaft 58. A 135 bevel gear 66 on each end of shaft 58, outside of the levers 62, meshes with a similar bevel gear 68 on the end of a rocker shaft 60, whereby rocking of the prime mover shaft 58 results in a similar and simultaneous rocking of the two shafts 140 60 which are geared thereto. And the third shaft 60 is geared at opposite ends to the other two shafts 60, so that rocking of all four shafts is consequent upon vertical movement of the 145 actuators 52.

The operation and effect in this form of the invention are similar to those in the preferred form. The moment a man enters upon pole 16^a the pole depresses against tension of spring 28^a, swinging the closure sections 50, 50' quickly and 150

simultaneously to wide open positions. And spring 28^a returns pole 16^a to normal position with consequent closure of sections 50, 50' when pressure on the pole is removed.

5 Still another modification of the invention is illustrated in Figure 10, where the closure sections 70 are normally held closed by the counter-weights 72, and are opened by pull of cables 74. One cable is provided for each section 70, and has 10 its lower end connected to the arm of a counter-weight 72 and its upper end connected to the top portion of the sliding-pole, with suitable intermediate guiding pulleys within the tubular pole-supporting structure, through which tubular supports the cables conveniently may extend.

15 The combined weight of the counter-weights 72, in this case is required to be enough to sustain the sliding-pole in its uppermost position. The weight of a man on the pole, however, will 20 overcome the effect of the counter-weights, and will depress the pole and swing the closure sections open.

It will be apparent that the invention is 25 capable of many and varied applications. Primarily it relates to pole-actuation of a closure regardless of the type or the location of the closure. The illustrated specific forms of closures and of operating connections may be regarded as representative of the wide variety intended to be included within the scope of the 30 appended claims.

I claim as my invention:

1. In apparatus for automatic control of a passageway, the combination of a closure for 35 the passageway; a guide element extending into the passageway along which a body may slide; means associated with said guide for yieldingly permitting limited movement of the guide in the direction of travel of said sliding body and as a 40 result of weight of said body while the body continues to slide; and connections between the guide and the closure, whereby said movement of the guide actuates the closure to open it while said body continues its sliding movement along 45 said guide.

2. In apparatus for automatic control of a floor hole in a building, the combination of a closure for said hole; a guide element extending through 50 said hole; yieldable supporting means for said guide element connected to said element only above said hole, and adapted to permit limited downward movement of the guide element consequent upon substantial downward pressure being made effective on the guide element; and connections 55 between said supporting means and the closure, whereby downward movement of the guide element actuates the closure to open it.

3. In apparatus for automatic control of a sliding pole hole in an upper floor of a building, the 60 combination of a sliding-pole extending through said hole; a closure for said hole; yieldable means supporting the pole and permitting depression thereof under downwardly directed pressure applied to the pole; and connections between said 65 pole and said closure, whereby depression of the pole actuates the closure to open it.

4. In apparatus for automatic control of a sliding-pole hole in an upper floor of a building, the combination of a sliding-pole extending 70 through said hole; a closure for said hole; means above said floor for suspension of the pole, including a spring permitting limited depression of the pole when a substantial downward pressure is exerted thereon; and connections between the

pole and the closure, whereby depression of the pole actuates the closure to open it.

5. In apparatus for automatic control of a sliding-pole hole in an upper floor of a building, the combination of a sliding-pole extending through said hole; a sectional closure for said hole, each section being mounted for rotary motion about a horizontal axis; yieldable means supporting the pole and permitting depression thereof when a substantial downward pressure is exerted thereon; and connections between the pole and each said section of the closure, whereby downward motion of the pole is translated into rotary motion of said closure sections, to open them.

6. In apparatus for automatic control of a sliding-pole hole in an upper floor of a building, the combination of a sliding-pole extending through said hole; a sectional closure for said hole, each section being mounted for rotary motion about a horizontal axis; yieldable means supporting the pole and permitting depression thereof when a substantial downward pressure is exerted thereon; connections between the pole and a section of the closure, whereby movement of the pole actuates that section; and inter-connections between the sections of the closure, whereby actuation of one section results in simultaneous actuation of all.

7. In apparatus for automatic control of a sliding-pole hole in an upper floor of a building, the combination of a sliding-pole extending through said hole; a closure for said hole; a guard structure on said upper floor, around said hole, including a tubular upright; an actuator yieldingly supported in said tubular upright, on which actuator the sliding-pole is suspended; and connections between said actuator and the closure; said actuator being depressible by downward pressure on said pole, whereby the closure is actuated to open position.

8. In apparatus for automatic control of a sliding-pole hole in an upper floor of a building, the combination of a sliding-pole extending through said hole; a sectional closure for said hole, each section being mounted for rotary motion about a horizontal axis; a tri-pod guard structure around said hole, each leg thereof having an outer portion rigid on the floor, and an inner telescoping portion which extends upward 110 out of the rigid portion and has suspending connection to the pole at a high up location, and which extends downward within the said floor; spring means in each leg of the tri-pod yieldably supporting the pole suspending portions thereof 115 in uppermost positions; and connections between the said downwardly extending portions of the tri-pod and the closure sections, whereby a depression of the pole effects opening movement of the respective sections of the closure.

9. In apparatus for automatic control of a floor hole in a building, the combination of a sectional closure for said hole, arranged on the under side of said floor, each section being mounted for rotary motion about a horizontal axis; a guide element extending through said hole, and through said closure at a juncture of sections thereof; means supporting the guide element yieldingly, and permitting limited downward movement thereof under applied pressure; and a connection 140 between the guide element and each closure section, whereby movement of the guide element actuates the closure sections simultaneously.

THOMAS S. MCINTIRE.
